UNITED STATES PATENT OFFICE.

CHARLES FRANKLIN REAM, OF LANSING, MICHIGAN.

CHUCK.

1,063,215.

Specification of Letters Patent.

Patented June 3, 1913.

Application filed June 18, 1912. Serial No. 704,280.

To all whom it may concern:

Be it known that I, CHARLES FRANKLIN REAM, a citizen of the United States, residing at the city of Lansing, county of Ing-
ham, and State of Michigan, have invented
certain new and useful Improvements in
Chucks, of which the following is a speci-
fication.

This invention relates to improvements
in chucks.

The main objects of this invention are,—
first, to provide an improved chuck which
permits or enables the changing of tools
while the spindle is being rotated. Second,
to provide an improved chuck having these
advantages, which is capable of manipula-
tion with one hand. Third, to provide an
improved chuck which is simple and inex-
pensive in structure.

Further objects, and objects relating to
structural details, will definitely appear
from the detailed description to follow.

I accomplish the objects of my invention
by the devices and means described in the
following specification.

The invention is clearly defined and
pointed out in the claims.

A structure which is a preferred embodi-
ment of my invention is clearly illustrated
in the accompanying drawing, forming a
part of this specification, in which:

Figure I is a side view of my improved
chuck. Fig. II is a perspective view of the
locking sleeve 10. Fig. III is a side eleva-
tion of the tool holder 7, with the spring 14
thereon. Fig. IV is a perspective view of
the body 1. Fig. V is a view partially in
longitudinal section on a line correspond-
ing to line 5—5 of Fig. I. Fig. VI is a cross
section taken on a line corresponding to line
6—6 of Fig. V. Fig. VII is a cross section
on a line corresponding to line 7—7 of Fig.
V. Fig. VIII is a cross section on a line
corresponding to line 8—8 of Fig. V.

Referring to the drawing, the body 1 of
my improved chuck is provided with a
tapered shank 2 adapted to fit the socket
of an ordinary drill spindle, not shown.
The body 1 in the structure illustrated, is
formed of two pieces for convenience in
manufacture.

The body is provided with a cylindrical
socket 3 having a squared driving portion

4 at its inner end and an enlargement 5 at
its outer end, there being an annular col- 55
lar shoulder 6 at the inner end of the en-
largement.

The tool holder 7 is provided with a
squared driving portion 8 at its inner end
adapted to coact with the driving portion 60
4 of the body socket. The tool holder is
provided with a collar 9 adapted to engage
with the shoulder 6 when the holder is in-
serted in the body.

A locking sleeve 10 is mounted upon the 65
body, the sleeve being provided with an an-
nular internal groove 11 and a slot 12. A
stop pin 13 on the holder engages this slot
to limit the rotative movement of the sleeve
on the holder. A spring 14 is arranged 70
within the groove 11 with one end of the
spring connected to the stop 13, the other
being connected to the sleeve at 14'. This
spring acts to hold the sleeve with one end
of its slot in engagement with the stop 75
pin 13.

The sleeve is provided with spaced cam
lugs 15 at its inner end and the body with
coacting spaced lugs 16 at its outer end.
The spaces between the lugs 16 are adapted 80
to receive the lugs 15 when presented end-
wise thereto.

In inserting the holder in the chuck body,
the holder is pushed into the body socket
and the locking sleeve turned rearwardly 85
until the lugs 15 slip between the lugs 16 of
the body. The locking sleeve is then re-
leased and the spring acts to force the lugs
into their engaging position. If the chuck
is rotating when the drill is inserted, it is 90
only necessary to hold the locking sleeve
and push inwardly thereon, the rotation of
the holder bringing the lugs into engaging
position.

To remove the tool holder, it is only nec- 95
essary when the spindle is rotating, to grasp
the sleeve and pull out thereon. It will be
obvious that this is a one hand operation
which is a very great convenience from an
operating point.

A further advantage of the structure, is,
that the changes can be made without the
liability of injury to the workman.

My improved chuck is simple and eco-
nomical in structure and is not likely to get 105
out of repair in use.

I have illustrated and described my improved chuck in detail in the form preferred by me and have not attempted to illustrate or describe the various modifications which I contemplate as such modifications will no doubt be readily understood by those skilled in the art to which this invention relates. I desire, however, to be understood as claiming my improvements specifically in the form illustrated as well as broadly within the scope of the appended claims.

Having thus described my invention, what I claim as new and desire to secure by Letters Patent is:

15. 1. In a chuck, the combination of, a body having a cylindrical socket with a squared driving portion at its inner end and an enlargement at its outer end, there being an annular collar shoulder at the inner end of 20 the enlargement; a tool holder having a squared portion at its inner end adapted to coact with the squared portion of said body socket and a collar adapted to engage said shoulder at the inner end of said enlargement; 25 a sleeve having an internal annular groove and a slot therein mounted on said holder; a stop pin on said holder engaging said slot of said sleeve to limit the movement of the sleeve on the holder; spaced cam lugs on the inner end of said sleeve; spaced coacting lugs on said body; and a coiled spring arranged in said groove of said sleeve, one end of said spring being connected to said stop, the other being 30 connected to said sleeve whereby the sleeve is automatically actuated by the spring to engage and retain said lugs in their engaging position.
2. In a chuck, the combination of, a body 40 having a cylindrical socket with a squared driving portion at its inner end and an enlargement at its outer end; a tool holder having a squared portion at its inner end adapted to coact with the squared portion 45 of said body socket; a sleeve having an internal annular groove and a slot therein mounted on said holder; a stop pin on said holder engaging said slot of said sleeve to limit the movement of the sleeve on the 50 holder; spaced cam lugs on the inner end of said sleeve; spaced coacting lugs on said body; and a coiled spring arranged in said groove of said sleeve, one end of said spring being connected to said stop, the other being 55 connected to said sleeve whereby the sleeve is automatically actuated by the spring to engage and retain said lugs in their engaging position.
3. In a chuck, the combination of, a body 60 having a cylindrical socket with a squared driving portion at its inner end and an enlargement at its outer end, there being an annular collar shoulder at the inner end of the enlargement; a tool holder having a 65 squared portion at its inner end adapted to

coact with the squared portion of said body socket and a collar adapted to engage said shoulder at the inner end of said enlargement of said socket; a sleeve mounted on said holder; a stop for limiting the rotative movement of the sleeve on the holder; spaced lugs on said sleeve; spaced coacting lugs on said body; and a spring arranged to act on said sleeve to engage and retain said lugs in their engaging position. 75

4. In a chuck, the combination of, a body having a cylindrical socket with a squared driving portion at its inner end and an enlargement at its outer end; a tool holder having a squared portion at its inner end adapted to coact with the squared portion of said body socket; a sleeve mounted on said holder; a stop for limiting the rotative movement of the sleeve on the holder; spaced lugs on said sleeve; spaced coacting lugs on said body; and a spring arranged to act on said sleeve to engage and retain said lugs in their engaging position. 80

5. In a chuck, the combination of, a body having a socket therein; a tool holder adapted to be inserted into said socket and having driving engagement with said body; a sleeve mounted on said holder for limited rotative movement thereon; spaced cam lugs on said sleeve; spaced coacting lugs on said body; and a spring arranged to act on said sleeve to engage said lugs and retain them in their engaging position. 90

6. In a chuck, the combination of a body having a socket therein; a tool holder adapted to be inserted in said socket and provided with a driving tang; a securing sleeve for said holder mounted for limited rotative movement thereon, said sleeve and body being provided with coacting engaging members; and a spring arranged to act on said sleeve to hold it yieldingly at the forward end of its movement, said engaging members on said sleeve and body being disposed so that they may be brought into engaging relation by the rearward rotation of said sleeve with said holder tang in driving engagement with said socket. 100

7. In a chuck, the combination of a body having a socket therein; a tool holder adapted to be inserted in said socket and provided with a driving tang; a securing sleeve for said holder mounted for limited rotative movement thereon, said sleeve and body being provided with coacting engaging members, said engaging members on said sleeve and body being disposed so that they may be brought into engaging relation by the rearward rotation of said sleeve with said holder tang in driving engagement with 110 said socket. 110

8. In a chuck, the combination of a body having a socket therein; a tool holder adapted to be inserted into said socket and having driving engagement with said body; a 130

sleeve mounted on said holder for limited rotative movement thereon, and a spring arranged to act on said sleeve to hold it yieldingly at one end of its movement; and coacting engaging members on said sleeve and body adapted to be engaged when the sleeve is actuated by the tension of said spring.

In witness whereof I have hereunto set my hand and seal in the presence of two witnesses.
